UNITED STATES PATENT OFFICE.

WILLIAM G. KENDALL, OF NEWARK, NEW JERSEY, ASSIGNOR TO HENRI RIGAUD, OF PARIS, FRANCE, ALSO KNOWN AS PARFUMERIE RIGAUD, OF NEW YORK, N. Y.

LIP-STICK HOLDER.

Application filed August 2, 1922. Serial No. 579,242.

To all whom it may concern:

Be it known that I, WILLIAM G. KENDALL, a citizen of the United States, and a resident of Newark, in the county of Essex and State of New Jersey, have invented a new and Improved Lip-Stick Holder, of which the following is a full, clear, and exact description.

The present invention relates to new and useful improvements in toilet articles, cosmetics and the like, and it pertains more particularly to a means for retaining lip sticks and similar forms of cosmetics.

It is one of the objects of the invention to provide a new and improved form of holder for lip sticks and the like in which the cosmetic may be enclosed within a casing or housing when not in use.

It is a further object of the invention to so construct the casing or housing that it is adapted to project the cosmetic therefrom when it is desired to use the same.

With the above and other objects in view, reference is had to the accompanying drawings, in which—

Figure 1 is a view in elevation of the cosmetic holder or container in closed position;

Figure 2 is a longitudinal sectional view thereof with the cosmetic in projected position; and

Figure 3 is a transverse sectional view taken on the line 3—3 of Figure 1.

Referring more particularly to the drawings, the reference character 11 designates the stick of cosmetic and said cosmetic stick is carried within a tubular container or the like 12. This tubular container 12 is mounted within a second tubular member 13 and passing through the said tubular member 13 is a screw 14, this screw 14 being permanently carried by the member 12. The tubular member 13 is provided with an elongated slot 15 in which the screw 14 is adapted to be received in order to permit of a sliding movement between the members 12 and 13.

The reference character 16 designates an outer container or housing and said outer container or housing is provided with a spiral slot 17 within which the screw 14 is adapted to operate.

The outer housing 16 is provided with an annular channel 18 and the member 13 is

provided with an annular bead 19 adapted to be received within the annular channel 18 to retain the members 13 and 16 together in operative relation. It is to be understood, however, that the annular bead 19 is freely revoluble within the annular channel 18.

In order to close the end of the member 16, a cap 20 is provided and said cap 20 is adapted to be removably engaged with the open end of the member 16.

The device operates in the following manner: When it is desired to use the cosmetic the cap 20 is removed and the lower end of the member 13 is grasped and said member 13 is rotated. As the member 13 is rotated the side edge of the slot 15 will engage the screw 14 and tend to rotate the same therewith. Upon rotating the member 13 the screw 14 passes through the spiral slot 17 and will cause the carrier 12 to move longitudinally of the member 16 and project the cosmetic 11 therefrom, as shown in Figure 2. After the cosmetic has been used it is retracted into the member 16 by rotating member 13 in the opposite direction and after the cosmetic has been retracted into the member 16 the cap 20 is again replaced to close the outer container or housing 16.

From the foregoing it is apparent that the present invention provides a new and improved form of cosmetic holder in which the cosmetic may be projected when desired for use and retracted when not in use in order that it may be contained within a sanitary enclosure when not in use.

Having thus described the invention, what is claimed is:

1. In a device of the character described, comprising an outer casing provided with a spiral slot, a tubular member mounted in said casing and provided with a straight slot, an article carrier mounted within said second tubular member, and means carried by the article carrier and projecting through the straight slot of the tubular member and the spiral slot of the outer member, whereby upon rotation of the tubular member the article carrier will be projected from the container.

2. As an article of manufacture, a container having a spirally disposed slot, a slotted tubular member mounted within said container and having one of its ends pro-

2
jected beyond the end of the container to provide means for rotating the tubular member within the container, an article carrier mounted within the tubular member, and 5 means carried by the article carrier and projecting through the slot of the tubular member and the spiral slot of the container

whereby upon rotation of the tubular member the article carrier will be moved longitudinally of the tubular member to project 10 the article carried thereby from the end of the container.

WILLIAM G. KENDALL.

DISCLAIMER

1,480,449.—*William G. Kendall, Newark, N. J. LIP-STICK HOLDER.* Patent dated January 8, 1924. Disclaimer filed May 23, 1930, by the assignee by mesne assignments, *Parfumerie Rigaud, Inc.*, and ratified by the patentee.

Hereby enters a disclaimer in and to said claim 1 as follows:

It herewith disclaims from the scope of claim 1 of said patent any device of the character described in which the tubular member having the straight slot does not project beyond the end of the outer member which has the spiral slot, and in which said tubular member (having the straight slot) does not have a lateral enlarged portion adjacent the inner end of said outer member (having the spiral slot), said enlargement operating to limit the longitudinal movement of said outer member (having the spiral slot) with respect to said tubular member (having the straight slot), when the outer member and the tubular member are assembled.
